UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

SILUB-CATCHER.

1,391,331.

Specification of Letters Patent. Patented Sept. 20, 1921.

Application filed September 18, 1920. Serial No. 410,637.

To all whom it may concern:

Be it known that I, JOHN O. MCKEAN, a citizen of the United States, and resident of Westfield, in the county of Hampden and 5 State of Massachusetts, have invented a new and useful Improvement in Slub-Catchers, of which the following is a specification.

The object of my invention is to provide a novel slub catcher which will be very 10 simple in construction and effective in operation and in which the width of the slit through which the line passes may be varied by springing one of the members of the device out of its normal position, this 15 result being accomplished without changing the parallelism of the walls of the slit.

My slub catcher more specifically comprises a bracket having an integral resilient yoke, the branches of which are provided, 20 with lateral extensions which form between them the slit for the passage of the yarn; means being provided, such for instance, as an adjusting screw which spans the yoke members, for springing one of the members 25 out of its normal position toward the other member to narrow the slit for adapting it to different sizes of yarn.

A further object is to combine the slub catcher with a yarn tension. 30 A practical embodiment of my invention is represented in the accompanying drawings, in which,

Figure 1 represents the slub catcher in top plan.

Fig. 2 represents the same in side elevation.

Fig. 3 represents a rear elevation.

Fig. 4 represents a front elevation.

Fig. 5 represents a section taken in the 40 plane of the line V—V of Fig. 1.

The bracket is preferably a casting which comprises a resilient yoke, the lower branch of which is designated by 1 and the upper branch by 2. These two branches at their 45 free ends are provided with lateral extensions 3 and 4 respectively, forming between them a slit 5 for the passage of the yarn. These lateral extensions 3 and 4 may be provided with downwardly and upwardly 50 extended ears 6 and 7 respectively. A pin 8 projects downwardly from a lug 9 on the back of the upper lateral extension 4, across

the slit 5, which pin serves as a guide for the yarn passing through the slit.

The means which I have shown for 55 springing the upper branch 2 of the integral resilient yoke out of its normal position to vary the width of the slit 5 without changing the parallelism of its walls is herein shown as an adjusting screw, the shank 10 of which passes through the upper branch 2, across the yoke into screw-threaded engagement with the lower branch 1, the head 11 of which screw is preferably countersunk in a recess 12 in the upper branch 2. 60 As the device is shown, the screw is arranged to spring the upper branch 2 toward the lower branch 1 of the yoke to narrow the yarn slit, the spring in the upper branch 2 serving to widen the said slit as the adjusting screw is unscrewed. 65

The bracket may be supported in any 70 suitable manner on the bar 13 of the machine, as for instance, by providing the lower branch 1 of the yoke with a hollow lug 14 through which the bar 13 extends, a set screw 15 being provided for securing the bracket on the bar. 75

A tension for the yarn is carried by the 80 upper branch 2 of the yoke and comprises generally a vertical pin 16 on which is loosely mounted a weighted disk 17, between which and the table 18 the yarn passes on its way to the slit 5. A suitable guard 19 is secured on the pin 16 by a set screw 20. 85 A guide finger 21 projects forwardly from the bracket in position to guide the yarn to the tension.

It will be seen from the above description 90 that I have provided a device which will engage bunches, slubs, knots or other enlarged portions of the yarn, which device may have its slit enlarged or ensmallled to suit yarn of different sizes, the means for varying the width of the slit being extremely simple and capable of adjusting the width of the slit without changing the parallelism of its walls. 95

It will also be seen that the device is extremely simple, having a minimum number 100 of parts for accomplishing the results set forth.

It is evident that various changes may be made in the construction, form and arrange-

ment of the several parts without departing from the spirit and scope of my invention; hence I do not wish to limit myself to the particular construction herein shown and described; but—

What I claim is:

1. A slab catcher comprising an integral resilient yoke, the branches of which have between them a slit for the passage of the 10 yarn, said slit having parallel walls, and means for springing one of the branches out of its normal position to vary the width of the slit and at the same time to maintain the parallelism of its walls.
- 15 2. A slab catcher comprising an integral resilient yoke, the branches of which form between them a slit for the passage of the yarn, said slit having parallel walls, and means for springing one of the branches to 20 toward the other branch to narrow the slit and at the same time to maintain the parallelism of its walls.
- 25 3. A slab catcher comprising an integral resilient yoke, the branches of which have lateral extensions forming between them a slit for the passage of the yarn, said slit having parallel walls, and means for springing one of the branches out of its normal position to vary the width of the slit and 30 at the same time to maintain the parallelism of its walls.

4. A slab catcher comprising an integral resilient yoke, the branches of which have lateral extensions forming between them a slit for the passage of the yarn, said slit 35 having parallel walls, and means for springing one of the branches toward the other branch to narrow the slit and at the same time to maintain the parallelism of its walls.

5. A slab catcher comprising an integral resilient yoke, the branches of which form between them a slit for the passage of the 40 yarn, said slit having parallel walls, and a screw spanning the branches for springing one of the branches out of its normal position to vary the width of the slit and at the 45 same time to maintain the parallelism of its walls.

6. A slab catcher comprising an integral resilient yoke, the branches of which form between them a slit for the passage of the 50 yarn, said slit having parallel walls, and a screw spanning the branches for springing one of the branches toward the other branch to vary the slit and at the same time to 55 maintain the parallelism of its walls.

In testimony that I claim the foregoing as my invention, I have signed my name this 9th day of September, 1920.

JOHN O. McKEAN.
